WIRE STRIPPER FOR STRIPPING OUTER CONDUCTORS FROM COAXIAL LINES

John E. Helminak, Washington, D. C., assignor to the United States of America as represented by the Secretary of the Navy

Application January 27, 1949, Serial No. 73,178

1 Claim. (Cl. 81—9.5)

1

The present invention relates to tools, commonly known as "wire strippers," for use in removing an outer covering from a conductor. More specifically, it relates to strippers for facilitating the removal of the outer conductor from a coaxial pair.

Wire strippers are known wherein one element includes a pair of grippers, for holding a wire by its insulation, while the other element includes means for cutting through said insulation and pushing the latter away, beyond the cut thus made.

However, the insulation that is handled successfully by strippers of this kind is, in general, much easier to cut than the conductor enclosed therein, and difficulty arises when it is attempted to strip, from a soft copper wire having enamel insulation thereon, a tough metal covering, such as the tubular outer conductor of a coaxial pair. If the cutters are powerful enough to cut the tubing, they will simultaneously crimp it about the inner wire and also leave a burr, often short-circuiting the conductors of the pair, and also tending to nick and thus leave a weakened region of the central conductor at the cut. The present invention overcomes this defect by providing a modified type of cutter, and additional members acting both as stops and as grippers.

An object of the invention is to provide a stripper which will make it easy to remove a desired portion of the outer metallic conductor, to expose a corresponding length of the insulated inner one, without injuring it or causing a break or a short circuit between the conductors.

Other objects and many of the attendant advantages of this invention will be appreciated readily as the same becomes understood by reference to the following detailed description, when considered in connection with the accompanying drawings, wherein:

Fig. 1 is a front view of the stripper, partly broken away and in section;

Fig. 2 is a fragmentary side elevation;

Fig. 3 is a fragmentary detail, on an enlarged scale, showing a coaxial conductor gripped and nicked by the stripper;

Fig. 4 is a perspective view of one of the nickers, on a still larger scale;

Fig. 5 is a fragmentary detail, corresponding to Fig. 3, but showing the opposite side of the stripper, and showing a coaxial conductor gripped in the jaws, with its tubular outer conductor completely cut and ready for removal;

Fig. 6 is a view showing the same structure as Fig. 5, but with the jaws separated, and the cut end of the outer conductor stripped off;

Fig. 7 is a fragmentary elevation, partly in section, on the plane 7—7 of Fig. 6;

2

Fig. 8 is an end view of the stripper, with the jaw-end toward the observer; and

Fig. 9 is a much enlarged elevation, partly in section, of a fragment of coaxial conductor that has been nicked and is ready to have its tubular conductor broken.

For convenience, the invention will be disclosed as embodied in a modified form of a known type of stripper, described in U. S. Patents 1,730,980 and 2,179,581. The detail structures of such conventional strippers are retained, as far as the manipulating means are concerned, only the operating head being changed.

Referring first to Fig. 1, the conventional tool 15 comprises two handles, 1, 2, resembling those of pliers and the like. Two levers 3 and 4 are pivoted together by a pivot screw 5, and are attached to the respective handles by pins 7 and 9, slidably engaged in the inclined slots 8 and 10 in said levers.

Suitable relatively weak wire springs 21 and 22, housed in the handles 1 and 2, conveniently made of sheet metal stamped into U-section, bear against the levers 3 and 4, partly housed therein, 25 to keep the handles separated when in their idle positions, as illustrated.

A relatively strong spring 6 bears against the lower ends of levers 3 and 4, urging them apart, and thus holding together the upper ends of said levers, beyond the pivot screw 5.

According to the present invention, the upper end of levers 3 carries a jaw member 13, which is secured to said lever by a pair of screws 15, passing through lugs 19 on opposite sides of, and 35 integral with, said lever, one of the said screws being shown in Fig. 1. A coacting jaw member 14, which may be exactly like the jaw member 13, is similarly carried by the handle 1, by means of screws 16.

It will be understood that each jaw member 13 and 14, has a gripper or jaw portion on one side thereof connected by integral "through" portions that serve to hold the jaws aligned and, in the case of members 14 and 14a, also bear slidably again the inner edges of levers 3 and 4 respectively, to guide the handles 1 and 2 in operation.

On the ends shown in Fig. 1 these jaw members 13 and 14 clamp the nickers 17 and 18 between themselves and lugs 19 and 20, provided on lever 3 and handle 1 respectively. These nickers preferably are thin steel blades, resembling the wafer-type blades in common use in safety razors. Their function is to produce nicks in opposite sides of the tubular conductor at the location where it is to be severed.

In the conventional type of stripper, when facing the front of the latter, cutting jaws are pro-

vided on one side of the tool, usually the right-hand side, while the grippers are on the left side. In the present device it is preferred to locate the nickers on the left; and to omit the grippers entirely. This absence of grippers from the front or "first" side of the tool is evident clearly in Fig. 1.

The nickers are preferably alike and thus interchangeable, and are shaped as shown in Fig. 4. While nicker 17 alone is illustrated, it will be understood that, if inverted, the illustration would equally well picture the nicker 18 in operating position. Each nicker comprises a blade 23 having a sharpened edge 24 and two slots 25 and 26. One corner of the blade 23 is cut away, making said nicker of inverted L-shape.

As stated above, each nicker, 17 and 18, is held in place by the corresponding jaw member, 13 and 14 respectively, by clamping it between said member and the lugs 19 and 20. This may be accomplished by screws 15 and 16, which pass through the slots 25 and 26 of the nicker blades.

The other end of each jaw member has a jaw thereon, bent at right angles to the direction of the length of levers 3 and 4, as is shown best in Fig. 5. It will be understood that the jaw members 13 and 14 that support the nickers have the wire-clamping jaws 27 and 28, that also serve as stop members, at their opposite ends, while the other two jaw members, 29 and 30, have no jaws at that face of the tool on which the nicking edges are located, but have the stops or gripping jaws 31 and 32 on their other ends. Preferably the work-gripping surfaces of said jaws are flat, and not serrated as in conventional strippers. This avoids injury to the relatively delicate tubular conductors to be gripped by said jaws.

Thus one face of the tool carries no wire holding or manipulating means except the nickers, whereas the other face has two pairs of jaws or stops which alternatively act as grippers. Each jaw member is supported by two lugs, with suitable screws passing through said lugs and threaded into the jaw member.

The operation of the tool is as follows:

The coaxial conductor that is to be stripped near its end is first suitably engaged by the tool, and the handles 1 and 2 brought together, to force the nickers 17 and 18 into the tubular outer conductor 33 to produce nicks 34 and 35 therein, as shown in Fig. 9. The nickers are so adjusted in the tool that even when the handles are squeezed together as far as possible, so that stops 27 and 28 are in engagement, the said nickers nevertheless are spaced apart sufficiently to prevent injury to the inner conductor 36 of the coaxial pair, or even to force the tubular conductor 33 into contact with said inner conductor. This adjustment varies for different sizes of coaxial conductors, and is made possible by the slots 25 and 26 of the nickers 17 and 18.

Having nicked the outer conductor 33, the coaxial conductor is gently bent back and forth, manually, most easily but not necessarily while still engaged between the nickers, to sever or cut said outer conductor 33 in the plane of the nicks. Some care is necessary to avoid injuring the inner conductor 36 in the course of this manipulation, and consequently the bending should not be through too great an angle.

The coaxial conductor, with its outer tubular conductor severed, is next placed again in the tool, but this time on the rear or "second" side of the tool, in the position shown in Fig. 5. This view shows the coaxial conductor clamped in place, by the initial closing movement of the jaws

that occurs when the handles 1 and 2 first are brought together partly. Continued squeezing on the said handles will cause the other end of the tool to open, thus separating the two sets of gripping jaws, with the result shown in Fig. 6, that is, with the severed end of the outer conductor separated from the inner conductor. More specifically, the left hand jaws grip and hold the complete coaxial conductor, while the right hand jaws grip only the severed end of the outer conductor 33, and pull it off the insulated inner conductor 36.

The nicker blades 17 and 18 may be replaced from time to time, as they become dulled. This replacement is easy because of the slots 25 and 26, which make it unnecessary to remove the screws 15 and 16, which need merely be loosened to permit removal of the worn out blades and insertion and adjustment of the new ones in place thereof.

It will also be seen that while the invention has been disclosed with reference to one specific type of strippers, other types may also be used, for instance, that described in U. S. Patents 1,151,319 and 1,196,322, by making suitable changes in details.

Obviously many other modifications and variations of the present invention are possible in the light of the above teachings. It is therefore to be understood that within the scope of the appended claim the invention may be practiced otherwise than as specifically described.

What is claimed is:

A wire stripper for use in removing the outer conductor from a coaxial cable, comprising two pivotally-connected members, one of said members carrying on its first side a pair of nickers having opposed straight nicking edges, said nickers being slideable toward and from each other while maintaining said nicking edges parallel to each other, means comprising engageable stops mechanically connected with said nickers and slidably carried on the second side of said member to predetermine the minimum separation of said nickers, said stops being designed alternatively to act as grippers, the other member being unobstructed on the corresponding first side to permit the cable to extend freely between the nickers, and a pair of stops acting as grippers slidably carried on the second side of the other member to coact with the first pair of grippers, whereby the outer conductor of the cable may be gripped on opposite sides of nicks previously made by the nickers, and pulled off the end of the central conductor.
